AUTOMATIC FIRE AND BURGLAR ALARM

Anton Kohlndorfer, Miesbach/Oberbayern,
GermanyApplication June 16, 1933, Serial No. 676,102
In Germany May 6, 1932

5 Claims. (Cl. 116—106)

The present invention relates to an automatic fire alarm, the main advantage of which, in contrast to fire alarms of known type, resides in the fact that it does not require any special knowledge on the part of the user. The fire alarm can be fitted by an amateur at a suitable place without its being necessary to arrange any electric switch or the like. The cost of production is very small.

10 The fire alarm consists of a mechanical-acoustic signal mechanism with a setting device which is adapted to be held in the set position by means of an easily fusible or easily combustible substance (for instance, wax, a combustible cord or the like). In this arrangement the signal-release member rests on the easily fusible substance. The bearing surface of the release member can be widened. The signalling mechanism is contained in a housing, from which the release member protrudes, and the easily fusible substance is disposed outside on the housing. The said substance is carried by a detachable frame, socket or the like.

15 A burglar alarm may be combined with the fire alarm. With this object in view the easily fusible, exposed substance engages with a tensioned band, thread or the like. The band or thread may also engage on a rocking lever carrying the substance in an exposed manner.

20 The attached drawing shows three typical forms of construction of the fire alarm according to the invention, Fig. 1 showing the first form in elevation and Figs. 2 and 3 showing two modifications of the alarm control mechanism.

25 According to Fig. 1, in a housing 1 there is accommodated a clockwork mechanism of known type which by means of a striker is adapted to actuate a bell 2. The wound-up clockwork is held in the locked position by a lever 3 projecting outside the housing. This lever, under the influence of a spring or a weight, tends to swing downwards in the direction indicated by the arrow and thereby to release the clockwork. It rests, however, on an easily fusible substance 4, 30 which is carried by a pan.

35 As the easily fusible substance there may be used paraffin or other wax, resin, artificial resin, but also easily fusible metals or alloys. If, in consequence of an outbreak of fire, the temperature of the room in question rises, the easily fusible mass 4 melts, the lever 3 no longer meets with resistance and falls thus releasing the clockwork mechanism. The bell 2 then rings.

40 Instead of easily fusible substances, easily combustible substances may also be used. Thus, for

instance, to the lever 3 there may be attached a cord 3 (indicated by dotted lines in Fig. 1) which holds the lever in the horizontal position, said thread being stretched across the room to be protected, so that when the thread is burnt through or broken at any spot, the alarm signal is released.

45 In this case the fire alarm is at the same time a burglar alarm. For the same purpose the frame 5 carrying the easily fusible mass may also be carried by one arm of a rocking lever 6 to the other arm of which there is attached a cord or the like 7, which is stretched across the room in question. The double-lever 6 is adjusted in a condition of equilibrium. If unauthorized persons enter the room and the cord is slightly moved, lever 6 and frame 5 will swing around their pivot 8 thereby releasing lever 3 and in turn the signalling mechanism.

50 In the form of construction shown in Fig. 2, the container 5 holding the fusible mass 4 is integral with the lever 6 which pivots about a pin 8, so that when the cord 7 is pulled it swings with this lever and releases the lever 3.

55 According to Fig. 3, the bearing surface of the lever 3 is provided with a broadened portion to prevent it from sinking too easily into the easily fusible mass and releasing the clockwork mechanism. Measures should be taken to prevent the fire alarm from being set in operation unintentionally in consequence of high external temperature. The pan 5 carrying the fusible mass 4 is, according to Fig. 3, suspended on a lever 9 and held in fixed position by a hook 10. As soon as the hook 10 is released by a pull on the cord 7 or by pressure on its upward prolongation 11, the lever 9 together with the pan 5, falls and releases the lever 3, which is loaded by a spring 12 and a sliding weight 13, so that the bell rings.

60 If it is intended that the apparatus according to Fig. 3 shall answer to heat and fire, the pivoting arm 10, 11 is put out of operation by tying it back, whereby the lower hooked end of the arm 10 does not engage with the pan 5. Then the safety cord is fixed in a hole 23 provided for this purpose at the upper end of the pan 5, this cord is drawn, for instance, through an opening 24 of a pivoted arm 21, and then the cord is stretched across the room to be protected in such manner that the pan is raised, and thus the apparatus is in the set position. Now if the cord is burnt through at any place the tension ceases, the pan which is connected to the lever 9 sinks and the apparatus comes into operation. If again a high temperature occurs in the room protected in this manner

without flames being formed, the signal release lever 3 sinks into the fusible mass 4 which has become soft and releases the alarm mechanism.

Further modifications may be made while employing the principle on which the present invention is based.

It is evident that the cost of production of the device according to the invention is extraordinarily low, and that the device can be manipulated by any non-expert. As the easily fusible mass is contained in special pans or frames it is impossible for the mass to become distorted under the influence of a high natural external temperature which, however, is not capable of causing the mass to melt. The apparatus comes into operation only when fire has actually broken out, or when there is immediate danger of fire (overheating of a story of a house). The pans containing the fusible mass 4 can easily be exchanged by a non-expert.

On the housing 1 terminal contacts or contacts of other type 14 (Fig. 1) can be fitted which are conductively interconnected by the falling lever 3. Thus it is possible to set a remote bell mechanism or a visual signal in operation.

Further, a device may be provided which indicates whether the apparatus is set or whether the clockwork mechanism is wound up or not. With this object in view, in the form of construction shown in Fig. 3 there is mounted on the housing 1 a lever 16 provided with a signal disc 15 which at the same time serves as a loading weight. To the free end 17 of this lever is secured a cord 20 wound on a small drum 18 of the clockwork shaft. When the clockwork is wound up the cord 20 is wound up and the lever 16 moves into an approximately vertical position, in which the signal 15 is visible. When the clockwork is run down the cord 20 is unwound and the lever 16 falls under its own weight. It is obvious that the arrangement can also be such that the signal disc 15 is visible only when the clockwork has run down and is covered when the clockwork is wound up.

Having now particularly described and ascertained the nature of my said invention and in what manner the same is to be performed, I declare that what I claim is:

1. Alarm device comprising a signal mecha-

nism, a lever, heat responsive means carried by the latter, a flexible element retaining said lever and the means carried thereby in a condition of unstable equilibrium, and detent means normally supported by the heat responsive means in position to prevent operation of the signal mechanism.

2. Alarm device comprising a signal mechanism, a lever, heat responsive means carried by the lever, a flexible element retaining said lever and the means carried thereby in a condition of unstable equilibrium, and detent means normally supported by the heat responsive means in position to prevent operation of the signal mechanism, said heat responsive means comprising a pan containing a fusible mass.

3. Alarm device comprising a signal mechanism, a lever, heat responsive means carried by the latter, a flexible element retaining said lever and the means carried thereby in a condition of unstable equilibrium, and detent means normally supported by the heat responsive means in position to prevent operation of the signal mechanism, said heat responsive means comprising a pan containing a fusible mass, said flexible element comprising a cord, stretched across the room to be protected.

4. Alarm device comprising a signal mechanism, a lever, heat responsive means carried by the lever, a flexible element retaining said lever and the means carried thereby in a condition of unstable equilibrium, and detent means normally supported by the heat responsive means in position to prevent operation of the signal mechanism, said heat responsive means comprising a pan containing a fusible mass, said flexible element comprising a combustible cord, stretched across the room to be protected.

5. Alarm device comprising a signal mechanism, a lever, heat responsive means carried by the lever, a flexible element retaining said lever and the means carried thereby in a condition of unstable equilibrium, and detent means normally supported by the heat responsive means in position to prevent operation of the signal mechanism, said detent means comprising a rocking lever projecting from the signal mechanism.

ANTON KOHLNDORFER.
